T. O. BROOKS

CARD RACK

Filed Dec. 22, 1922

INVENTOR
T. O. Brooks.
BY Arthur C. Brown
ATTORNEY

UNITED STATES PATENT OFFICE.

THOMAS O. BROOKS, OF DALLAS, TEXAS, ASSIGNOR TO B/G SANDWICH SHOPS, INC., OF KANSAS CITY, MISSOURI, A CORPORATION OF MISSOURI.

CARD RACK.

Application filed December 22, 1922. Serial No. 608,459.

To all whom it may concern:

Be it known that I, THOMAS O. Brooks, a citizen of the United States, residing at Dallas, in the county of Dallas and State of Texas, have invented certain new and useful Improvements in Card Racks; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to a card rack and it is particularly adapted for use in holding order cards or slips for the use of chefs.

Obviously it is desirable to prepare food orders in the order in which they are received and unless some means is provided for systematically arranging the order cards or slips, confusion arises which causes misunderstandings between the patrons and the proprietors of the restaurants.

25 My invention contemplates the provision of means whereby the orders must be posted in the order of their receipt and whereby liability of confusion in filling them in their proper order will be eliminated.

30 The invention consists of certain novel parts and combinations of parts, which will be referred to hereinafter, reference being had to the accompanying drawings, in which—

35 Fig. 1 is a perspective view of a card rack constructed in accordance with my invention, the cards or slips being shown attached thereto.

Fig. 2 is a cross sectional view through the 40 card rack, one of the cards being shown in edge elevation, and

Fig. 3 is a cross sectional view through the card-supporting belt.

The invention is shown as consisting of a 45 bracket 1 having two horizontally disposed, diverging arms 2 and 3, to which is secured a horizontal, elongated bar 4, at the ends of which are supported two pulleys 5 and 6, both of them idlers. The pulleys are sup-

ported by the bolts 7 and 8, which are suspended from the bar 4 by the nuts 9 and 10, the pulleys being rotatable upon the bolts and resting upon the heads thereof, there being spacing sleeves 11 and 12 for spacing the pulleys 5 and 6 away from the bar 4. 50 55

Passing around the spaced pulleys is a card-supporting belt 13, having a plurality of card or slip-receiving clips 14 thereon. Each clip is shown as comprising a bar 15, having its upper end bent backward and inwardly to form a spring tongue 16 to receive one of the cards or slips 17. The bar 15 may be fastened to the belt by a staple 18. The waiter or attendant will place the first order card in the clip nearest to the left hand side 60 65 of the card rack, the second order in the next succeeding one toward the right, etc. The chef will always remove the card nearest the left hand end and all subsequent orders will be fed to him on the belt from the right hand side. That is, when the first card, say the one designated '17', is taken off, he will advance the belt the width of one card so that '17'' becomes the nearest card and so on. Therefore, the orders can be taken care of 70 75 in their proper sequence.

The device is simple to construct, and it can be readily suspended from the wall of a room in full view of the chef or operator so that no confusion is likely to arise. 80

What I claim and desire to secure by Letters-Patent is:

1. A card rack comprising spaced suspended pulleys mounted on vertical axes, an endless belt passing around the pulleys with 85 its flat sides vertical and card engaging means carried by the belt.

2. A card rack comprising a bracket and a horizontal bar carried by the bracket, pulleys suspended from the ends of the bar 90 having vertical axes, a horizontal belt passing around the pulleys with the flat sides of the belt vertical and card engaging means carried by the belt.

3. A card rack comprising a bracket, a horizontal bar carried by the bracket, depending journals carried by the ends of the bar, pulleys mounted on the journals, an 95

endless belt on the pulleys having its flat sides in vertical planes and card engaging clips in spaced relation carried by the belt.

4. A card rack comprising a bracket having outwardly diverging, horizontal arms, a horizontal bar carried by the arms of the bracket, vertical bolts carried by the ends

of the bar, pulleys rotatable on the bolts, and a card-carrying belt passing around the pulleys.

10 In testimony whereof I affix my signature.

THOMAS O. BROOKS.
